ENCLOSED SWITCH

Raymond N. Rowe, Plainville, Conn., assignor, by
mesne assignments, to General Electric Com-
pany, a corporation of New York

Application March 15, 1950, Serial No. 149,849

3 Claims. (Cl. 200—133)

1

Modern electric apparatus especially enclosed switches employ cartridge type fuses. Sometimes these fuses have flat blade terminals and sometimes cap terminals. In any case, the fuses are removably supported by clips or clamps of various types.

When current is flowing through a switch, the fuses, being thermally functioning devices, generate heat, and since this heat has no ready means of escape, the fuses and adjacent terminals become very hot, and in time heat up the air in the switch enclosure, cause oxidation and annealing of various parts and increase of contact resistance at the fuse holders.

It is the main object of my invention to provide practical means applicable to various types of enclosed devices for preventing the overheating of the fuses and clamps and consequent damage.

It is another object to protect enclosed switches.

It is another object to protect enclosed devices having multiple fuses.

I have accordingly provided means for conducting heat from the fuse holders and radiating it outside the switch receptacle. For this purpose, I provide metallic rods or tubes thermally connecting the fuse holders but electrically insulating the rods or tubes which rods or tubes are connected to the opposite side walls of the receptacle and preferably to radiating fins or plates outside of the receptacle.

The accompanying two sheets of drawings show the preferred embodiment of the invention and one modification.

Fig. 1 is a front view of an enclosed switch embodying one form of my invention, the cover being broken away to show the interior.

Fig. 2 is a plan view of the form of Fig. 1, parts of the receptacle being broken away.

Fig. 3 is a side view of the radiating plates of Figs. 1 and 2.

Fig. 4 is a horizontal section showing a fragment of the thermal radiating members of Figs. 1 to 3 taken on the plane of the line 4—4 of Fig. 2.

Fig. 5 is a fragmentary sectional view taken on the plane of the line 5—5 of Fig. 2.

Fig. 6 is a front view showing a radiating rod with fuse terminal connections.

Fig. 7 is a side view showing one form of switch unit with fuse clamps and radiating rods.

Fig. 8 is a fragmentary horizontal section showing another form of radiating members.

The body 1 of the receptacle and the cover

2

2 are usually of metal, and enclose switch snap action and switch contact mechanism and fuses. In the form shown, the base 3 carries snap action mechanism of any suitable type. My Patents 2,468,463 and 2,475,338 and 2,494,314 may be referred to as suitable but not as limiting the invention herein claimed to such forms. The base is supported on flanges 4 at opposite sides of the receptacle and secured by screws 5. An actuating shaft 6 extends through the cover and is provided with a suitable handle (not shown).

The switching device 7 may be of any suitable type such for instance as that shown in my Patents 2,468,235 or 2,494,315 but the present invention is not limited to any special form. The movable switch member 8 is actuated by the crank shaft 9 from the snap action mechanism in base 3. The cross bar 10 extends across the receptacle and serves to actuate the various switch units, in this instance, three.

Each switch unit 7 has circuit terminals 11 and 12 of any suitable form and is provided with a circuit protection fuse 14 of any suitable form. In Figs. 1 and 2 and 5 the fuse has conventional cylindrical caps or ferrules and is removably mounted in spring clips 15, 15 of conventional form.

A fuse clamp 15 of Fig. 5 is mounted on each of a pair of spaced fuse terminals 16 on each switch unit by means of the extension 17 and screw 18. A metal rod 19 is connected to a fuse clip of each of the transversely situated switch units 7 by means of metallic straps 20, the ends of each of which are secured by a screw 18. Each strap encircles the rod 19 but is electrically insulated from its clamp by an insulating sleeve 21 which may be applied in any suitable manner. This strap may be perforated at 22.

A rod 19 extends across the outer side of the upper row of the fuse clamps and a bar 19' extends across the lower row of the fuse clamps, the fuses extending between the respective pairs of fuse clamps being substantially parallel as shown.

Each end of each rod is secured to a side wall of the receptacle by a screw 23 so as to radiate heat conducted from the transverse rods.

I also prefer to provide radiating metal plates 24 and 25 secured to the rods by screws 23, and 23' but spaced from the wall 1 by washers 26 and 26' so as to permit air to circulate around the plates.

In Fig. 6, I have shown a modification in which the various fuse terminals are insulated individually from the radiating cross members by insulating sleeves 30 which are inserted between the terminal straps 20' and the member 19. A

layer of metal foil 31 may be interposed between each strap and sleeve to increase local thermal conductivity.

In Figs. 6 and 7, the fuse 14' has terminal blades mounted in fuse clamps 15' such as set forth in my Patent 2,453,019. The form of clamp however is immaterial to the present invention. The end of strap 20' is secured between the fuse terminal 16' and clamp 15'.

In Fig. 8, I have shown a tubular radiating cross member 19x which is mounted in the receptacle by means of a screw threaded sleeve 23x. These sleeves may also support radiating plates 24x. These tubular radiating members provide increased radiating surfaces and permit circulation of air through the tubes.

From the foregoing, it will be seen that the cross rods or tubes constitute thermally conductive heat radiating extensions from the various fuse terminals and that they conduct heat to the side walls of the receptacle which in turn provide heat radiating surfaces outside the receptacle and the external plates or fins receive heat from the rods or tubes and serve as additional heat radiating surfaces.

Such an arrangement is especially valuable for minimizing the heating effect of the enclosed fuses since safety requirements make it necessary to so enclose the fuses that direct radiation from the fuses to the ambient atmosphere is impossible.

In the form shown, the cross rods or tubes not only serve as thermal radiating members but as they are secured to the side walls they help hold the switch mechanism and its fuses in place.

I claim:

1. The combination in an enclosed switch, walls forming an enclosure, a plurality of switching devices mounted in said enclosure, a pair of fuse terminals on each of said switching devices, a contact clip secured to each of said terminals for electrically connecting thereto and supporting one end of a fuse extending between each pair of said clips, said contact clips being positioned in such manner as to extend in two rows across said receptacle, two heat conducting rods in said enclosure extending across said enclosure respectively adjacent said rows of contact clips, a plurality of heat conducting members secured to each of said rods in electrically insulating heat conducting relation with said rods and secured each to one of said contact clips in heat conducting relation therewith, and means for securing opposite walls of said enclosure against the ends of said rods so as to form a heat conducting relation between the ends of said rods and said walls.

2. The combination in an enclosed switch, metal walls forming an enclosure, a plurality of switching devices mounted in said enclosure, a pair of fuse terminals on each of said switching devices, a contact clip secured to each of said terminals for electrically connecting thereto and supporting one end of a fuse extending between

each pair of said clips, said contact clips being positioned in such manner as to extend in two rows across said receptacle, two heat conducting rods in said enclosure extending across said enclosure respectively adjacent said rows of contact clips, a plurality of heat conducting members secured to each of said rods in electrically insulating heat conducting relation with said rods and secured each to one of said contact clips in heat conducting relation therewith, a heat radiating member on the exterior of said enclosure opposite at least one end of each of said rods, and means extending through opposite walls of said enclosure for securing said heat radiating member against the outer surface of its said wall and the ends of said rods against the inner surfaces of said walls so as to form a heat conducting relation between the ends of said rods, said walls and said heat radiating member.

3. The combination in an enclosed switch, metal walls forming an enclosure, a plurality of switching devices mounted in said enclosure, operating means for said switching devices extending through a wall of said enclosure, a pair of fuse terminals on each of said switching devices, a contact clip secured to each of said terminals for electrically connecting thereto and supporting one end of a fuse extending between each pair of said clips, said contact clips being positioned in such manner that said fuses are in substantial parallel relation with each other and said clips extend in two substantially parallel rows across said receptacle, two metallic heat conducting rods in said enclosure extending across said enclosure respectively adjacent the outer sides of said rows of contact clips, a plurality of metallic straps surrounding each of said rods, a layer of electrically insulating material between each of said straps and its said rod, each of said straps having end portions in engagement with each other secured to the adjacent contact clip in heat conducting relation therewith for the conduction of heat from said contact clip to its said rod, a heat radiating member on the exterior of said enclosure opposite each end of each of said rods, and clamping screws extending through opposite walls of said enclosure for securing said heat radiating members against the outer surfaces of said walls and the ends of said rods against the inner surfaces of said walls so as to form a heat conducting relation between the ends of said rods, said walls and said heat radiating members.

RAYMOND N. ROWE.
